(57) **CLAIM**

The ornamental design for a raceway for signage wiring, as
shown and described.

DESCRIPTION

FIG. 1 is an upper, front, perspective view of a raceway for
signage wiring embodying my new design, shown with a
cover panel thereof in an open position.

FIG. 2 is a left side elevational view thereof, the right side
being a mirror image thereof.

FIG. 3 is a front elevational view thereof.

FIG. 4 is a rear elevational view thereof.

FIG. 5 is a top plan view thereof; and,

FIG. 6 is a bottom plan view thereof.
